UNITED STATES PATENT OFFICE.

FRED EUGENE BROWN, OF INDIANAPOLIS, INDIANA, ASSIGNOR TO ZENITE METAL COMPANY, OF INDIANAPOLIS, INDIANA, A CORPORATION OF INDIANA.

WINDSHIELD.

Application filed March 22, 1920. Serial No. 367,972.

To all whom it may concern:

Be it known that I, FRED EUGENE BROWN, a citizen of the United States, residing at Indianapolis, in the county of Marion and State of Indiana, have invented a new and useful Windshield, of which the following is a specification.

The object of my invention is to produce a simple and efficient wind shield especially adapted for ready application, without a high degree of skill, to closed bodies of 10 automobiles.

The accompanying drawings illustrate my invention. Fig. 1 is a fragmentary elevation; Fig. 2 a side elevation on line 2—2 of Fig. 1, the glass and its frame having been removed; Fig. 3 an elevation on line 3—3 of Fig. 1; Fig. 4 a fragmentary section on line 4—4 of Fig. 1; and Fig. 5 a 20 fragmentary section on line 5—5 of Fig. 3.

In the drawings, 10 indicates a casting adapted to be placed in the upper corner of the front opening of a closed body formed by the body members 11 and 12, against 25 the inner face of the member 11. This casting 10 is provided, near its upper end, with a cylindrical pocket 13 and is split at 14 so that the pocket may be ensmalled by a clamping screw 15 passing freely through 30 the tongue 14' and threaded into the main body of the casting.

Rotatably mounted in pocket 13 is a trunnion 16 provided with a pair of ears 17 between which the adjacent portion of the 35 upper glass frame 18 may be secured.

Near its lower end, and on its rear face, casting 10 is provided with a lug 19 into which is threaded a clamping screw 20 engaging a friction block 21 which lies in a 40 suitably formed pocket in the upper face of lug 19.

Immediately above lug 19, casting 10 is pierced by an arc-shaped perforation 22 through which is passed a segment 23 attached at 24 to the frame 25 which carries an awning glass. Frame 25 is supported by a hinge 26 which is secured to the under face of a plate 27 adapted to be secured to the under face of the body member 12 which 50 defines the top edge of the front opening into the closed body. The forward edge of plate 27 is extended beyond hinge 26 and downturned as indicated at 27' to form an effective weather shield for the hinge. Opposite the middle of member 12, the plate 55

27 is provided with a sheet metal clip 29 adapted to retain a rubber wiper strip 30 adapted to contact with the upper glass frame 18 when said frame is in closed position.

Arranged in each lower corner of the front opening of the body, and secured to the inner edge of member 11, is a casting 40, preferably of the same thickness as casting 10. Near its upper end, and in its outer face, casting 40 is provided with a pocket 41 into which leads a slightly elongated opening 42 through which is projected the shank 43 of a trunnion member 44 the head of which is preferably of sufficient size 60 to cover opening 42 in all positions to which the trunnion-member may be shifted. Member 44 carries a pair of ears 45 to which the lower glass frame 46 is secured.

Mounted in pocket 41 is a segmental cylindrical bearing member 47 adapted to receive the shank 43 of trunnion member 44, said shank projecting laterally from the segmental bearing so that it may be forced against the face 41' of pocket 41. At opposite sides of its segmental bearing, member 47 is provided with oppositely-projecting ears 48, 49, one of said ears being arranged to bear against face 41'' of pocket 41 and the other being engaged by a clamping screw 50 threaded into the rear face of casting 40 into pocket 41. By this construction the lower glass frame may be raised, lowered and swung, and clamped in any desired position, the screw 50 serving not only to 70 ensmall the bearing around shank 43 but to also crowd said shank against surface 41' thus insuring a very firm holding of the glass frame with a comparatively light tightening of screw 50.

The vertical movability of the lower glass frame is provided in order to permit proper cooperation between said frame and the "fence" 55 which is secured to, and extends the length of the base-bar 56 of the opening into the closed body. The "fence" 55 is formed of sheet metal bent at one edge into an inverted vertical U, the free arm of which is slightly laterally resilient.

Secured to the lower bar of frame 46 is a 105 spring clip 57 adapted to straddle the U-portion of the fence, as indicated in Fig. 3.

The parts described may be arranged in a front opening of a closed body even though the dimensions thereof may vary to 110

a considerable extent and the gap between the upper end of casting 40 and the lower end of casting 10 may be filled by a wooden filler 60 which may be nicely fitted without great skill.

In order to provide a pleasing external finish, a sheet metal finish strip 61 may be introduced between member 75 and castings 10 and 40, said strip being held in place by the same fastening screws which are used to secure the castings in place. This finish strip comprises a main shank and a T-head (as shown in Fig. 4), formed by doubling an intermediate portion of the sheet upon itself and bending it substantially at right angles to the shank.

Each vertical side of the frames 18 and 46 carries a sheet metal clip 65 adapted to retain a rubber wiper-strip which will contact with the adjacent casting (and filler) where the frame is in closed position.

There is an almost unavoidable variation in widths of openings into the closed body, and difficulty has heretofore been experienced in fitting shields into such openings and having the supporting fittings properly cooperate with the swinging shield members. By providing the finish strip 61, I find that the commercial variations may be readily compensated by the insertion of a proper shim 75 under the main shank of the finish strip, as indicated in Fig. 4, the T-head of the finish strip serving to cover the shim from observation and the same fastening screws which hold the castings and finish strip in place also serving to hold the shim in place.

I claim as my invention:

1. In a wind shield, a main body, a segmental bearing-member movably carried on said body, a trunnion member journaled in and movable with said bearing-member and contacting with said main body, and a clamping member arranged to act upon said bearing member to clamp the same upon the trunnion member and the trunnion member against the main body.

2. In a wind-shield, a main body having a pocket, a segmental bearing-member mov-

ably mounted in said pocket, a trunnion member journaled in said bearing member and movable therewith, and a clamping member mounted in the main body and engaging the bearing member to clamp the same around the trunnion member and to force the trunnion member against the pocket wall.

3. In a wind-shield, a main body having a pocket, a segmental bearing member mounted in said pocket and having a pair of oppositely projecting ears, one bearing against a wall of the pocket, a trunnion member journaled in the bearing member, and a clamping member mounted in the main body and engaging the other ear of the bearing member to clamp said member around the trunnion and to force said trunnion against a wall of the pocket.

4. In a windshield, a main body, a segmental bearing, a trunnion member journaled therein and contacting with said main body, said bearing being shiftable relatively to said body to permit the trunnion to assume different positions, and a clamping member arranged to act upon said bearing to clamp the trunnion member against the main body.

5. In a windshield, the combination with a pair of side supports having pockets therein, a windshield mounted between said supports, an edge rail, said edge rail having a tongue-and-groove engagement with the edge of the windshield, segmental bearing members arranged within said pockets, trunnions on said windshield journaled in said bearing members and contacting with the walls of the pockets, and a clamping member arranged to act upon said bearing members to clamp the trunnion member against the walls of the pocket, said bearing members being bodily shiftable to permit the shifting of the windshield to make said tongue-and-groove engagement.

In witness whereof, I have hereunto set my hand at Indianapolis, Indiana, this 19th day of March, A. D. one thousand nine hundred and twenty.

FRED EUGENE BROWN.
